LOAD LIP FOR HAND TRUCKS

Melvin L. Reavis, Kansas City, Mo.

Application September 2, 1958, Serial No. 52,470

Term of patent 14 years

(Cl. D14—3)

Fig. 1 is a perspective view of a load lip for hand trucks embodying my new design;

Fig. 2 is a side view; and

Fig. 3 is a perspective of my load lip for hand trucks with the truck portion being shown in dotted lines for purpose of illustration.

This application is a continuation-in-part of my co-pending application for Patent Serial No. D. 48,354, filed November 6, 1957, now abandoned.

I claim:

The ornamental design for a load lip for hand trucks, as shown and described.
